UNITED STATES PATENT OFFICE.

CHARLES WIEBKE, OF NEWARK, NEW JERSEY.

CHENILLE-MACHINE.

1,114,086.

Specification of Letters Patent.

Patented Oct. 20, 1914.

Application filed November 11, 1912. Serial No. 730,578.

To all whom it may concern:

Be it known that I, CHARLES WIEBKE, a citizen of the United States, residing at Newark, in the county of Essex and State of New Jersey, have invented certain new and useful Improvements in Chenille-Machines, of which the following is a specification, reference being had therein to the accompanying drawings, forming part thereof.

My invention relates to chenille machines and particularly to machines for making ruff, or uncut chenille.

Objects of my invention are simplicity and compactness of construction, time and labor-saving convenience of manipulation and operation, and other objects and advantages which will hereinafter appear.

In a machine having a plurality of sets of loop-forming pins and feed-regulating rollers coöoperative therewith, for concurrently making a corresponding plurality of lengths of chenille, my invention includes means for independently varying the coöoperative relationship of the feed-regulating rollers and loop-forming pins of the different sets of chenille-forming mechanisms.

Heretofore in common practice all of a plurality of feed-regulating rollers for all of the corresponding number of loop-forming pins have been carried by a single or common shaft extending entirely across the machine and mounted in bearing brackets adjustable on the frame of the machine. This prior arrangement necessitates the simultaneous adjustment and a similar relationship of parts in all of the chenille-producing mechanisms embodied in a machine and precludes the possibility of making chenille of different sizes or of different varieties as to texture in the different lengths thereof made concurrently or of using different kinds or sizes of material in making the different lengths of chenille, but requires absolute unvarying uniformity in both material and product for all of the lengths of chenille made at the same time.

It is to be noted that my invention, in the improvements above noted, entirely overcomes all these defects, permitting, among other advantages, the use of loop-forming pins of different diameters for the different lengths of chenille.

My invention also includes means for rewinding the bobbins which supply surface thread to the fliers while such bobbins are

in the thread-supplying position on the machine. Commonly heretofore these bobbins have had to be removed from the thread-supplying position—necessitating the removal of the fliers also—and transferred for rewinding or replenishing to a separate winding mechanism mounted on the side of or over the machine, such machines taking up additional space because of the projecting winding mechanism. By my present invention, this separate winding mechanism is eliminated, the entire machine is rendered more compact, and the refilling of the bobbins is greatly facilitated.

My invention also includes other features of construction and combinations of parts, as will appear from the following description.

I shall now describe the chenille machine illustrated in the accompanying drawings embodying my invention and shall thereafter point out my invention in claims.

Figure 1 is a side elevation of the complete machine. Fig. 2 is a longitudinal central vertical section taken on a plane indicated by the line 2—2 of Figs. 3 and 6. Fig. 3 is a front elevation, partly in vertical section, on a plane indicated by the line 3—3 of Fig. 1. Fig. 4 is a front elevation, partly in vertical section, of the feed-regulating rollers and their adjuncts. Fig. 5 is a vertical section on a plane indicated by the line 5—5 of Fig. 4. Fig. 6 is an enlarged plan of the machine with parts omitted at the front and rear. Fig. 7 is a partial vertical section on a plane indicated by the line 7—7 of Fig. 6. Fig. 8 is a further enlarged vertical section on a plane indicated by the line 8—8 of Fig. 7. Fig. 9 is an enlarged longitudinal view of a short piece of the completed uncut chenille.

The chenille machine illustrated in the drawings as embodying my present invention is adapted to produce only uncut chenille, known also to the trade as ruff and as frill, and is a double machine, having a duplication of parts for producing two lengths of chenille at the same time. In each of the chenille-forming mechanisms of this machine, a stationary arbor 1, firmly fixed at its rear end in a supporting standard 2, removably carries a stationary loop-forming pin, such as 3 or 3*, at its enlarged forward end and in its middle portion serves as a bearing for the sleeve 4 of a flier having arms 5. The enlarged shank of the loop-

forming pin, which enters the enlarged terminal portion of the bore of the arbor 1, is grooved (Fig. 7) for the passage of the primary binder thread *a*, which is supplied along the surface of the projecting loop-forming portion of the pin 3 (or 3*) through the hollow arbor 1 from a spool 6 at the rear of the machine. Loop-forming pins having loop-forming portions of either larger or smaller diameter (the pins 3 and 3* being examples of two sizes) may be interchangeably substituted in the arbor 1 of either of the chenille-producing mechanisms for producing chenille having correspondingly longer or shorter surface loops, as desired, a machine embodying my present invention being particularly adapted to permit such substitution of loop-forming pins, as hereinbefore mentioned and as will hereinafter more particularly appear. The loop-forming surface thread *c* is wound about the loop-forming portion of the pin 3, and at the same time about the primary binder thread *a*, by the arms 5 of the rotating flier (only one of these arms being used at a time, the other effecting rotary counterbalancing), the surface thread *c* being supplied to the flier from a bobbin 7 journaled on the sleeve 4 of the flier. The secondary binder thread 40 *b* is supplied along the loop-forming portion of the pin 3, at the outside of the coils of the surface thread *c*, by a metal feed-regulating roller 8 which is driven and controls the coils of the surface thread *c* in their movement forward and from the pin 3 to form the surface loops of the uncut chenille, the feed-regulating roller 8 having a slight circumferential groove to guide the thread *b* which is supplied from a spool 9 at the front of the machine, the thread *b* passing around an intermediate tension pulley 10. The feed-regulating roller 8 is also milled or provided with fine longitudinal striations, as is usual, so it can effectively perform its coil-controlling operation.

My invention involves the means for mounting and driving the feed-regulating rollers 8 and means for rewinding the bobbins 7 with thread while the bobbins are in position on the sleeves 4 of the fliers.

Each feed-regulating roller 8 is mounted to yield bodily away from the loop-forming pin 3, or 3*, to permit the passage of lumps or knots in the material. Each feed-regulating roller is also provided with means for independently varying its co-operative relationship with the loop-forming pin, to provide for the use of different sizes of yarn or thread and for the employment of loop-forming pins of different diameters, such as the pins 3 and 3*, as well as to assure proper regulating or loop-controlling pressure.

In carrying out the present invention, each feed-regulating roller 8 is rotatively mount-

ed on a short shaft 11 rigidly carried by a vertically adjustable block 12 guided in a vertical slot in a post 13 and adjustable by means of a thumb screw 14 passing loosely through the top of the post and passing vertically through and having screw-threaded engagement with the block 12. The block 12 is provided with a lateral guide flange, as shown in the drawings, on its side adjacent to the feed-regulating roller 8, but at the opposite side of the post 13 a loose washer 15 is carried by a stud 16 which rigidly projects from the block 12, a strong coiled spring 17 being interposed between an adjusting nut screw-threaded on the stud 16 and the washer 15. The hole at the top of the post 13 for the free passage of the screw 14 is laterally enlarged at the side adjacent to the roller 8 (Fig. 4), and the head of the screw slidably bears on the top of the post. When any abnormal pressure comes on the feed-regulating roller 8, such as by reason of a lump or knot in the material, the spring 17 will yield to permit a downwardly angular bodily movement of the feed-regulating roller 8, thereby permitting the lump or other enlargement to pass without trouble. To provide for using different sizes of yarn or for employing loop-forming pins of different diameters, the feed-regulating roller 8 may be raised or lowered by manipulating the screw 14.

All of the feed-regulating rollers 8 (being two in number in the machine illustrated in the drawings) are driven from a single common cross-shaft 18. Each feed-regulating roller 8 is separately driven by a train of three intermeshing gears 19, 20 and 21, of which the gear 19 is fixed on the cross-shaft 18, the gear 21 is carried by a boss or sleeve 105 forming an extension from the roller 8, and the middle gear 20 is an idler carried by the pindle 22 of pivoted elbow-links 23 and 24 fulcrumed, respectively, on the cross-shaft 18 and the short roller-supporting shaft 11, 110 the pindle 22 being rigidly fixed in one of these links, such as in the link 23. This arrangement of gears permits the adjustment of the feed-regulating roller, herein before described, without affecting the driving thereof. 115

The means shown for driving the common cross-shaft 18 are a counter-shaft 25 and cone pulleys 26 and 27 connected by a crossed belt 28, the counter-shaft 25 being driven by a sprocket chain 29 from a main shaft 30, 120 the latter being provided with a fast pulley or driving pulley 31 and a loose pulley 32, as is usual.

During the chenille-forming operation, the fliers 4-5 are actuated from the driving pulley 31 through the intermediary of a longitudinal shaft 33 geared to the main shaft 30 and connected by a sprocket chain 34 with an upper longitudinal stub shaft 35, which in turn carries a large spur gear 36 130

meshing with two pinions 37 fixed, respectively, on the sleeves 4 of the two adjacent fliers. The direction of rotation of the fliers when viewed from the front of the machine is counter-clockwise, as indicated by arrows in Fig. 3. The surface thread *c* causes the bobbins 7 to rotate in the same direction as the fliers, but somewhat faster, due to the using of the thread from the bobbins. The 10 rotation of the bobbins 7 is controlled by a weighted brake cord 38 engaging V-grooves in the rear rims or flanges of the bobbins, as is common in the art.

The mechanism for rewinding the bobbins 7 is actuated from the loose pulley 32. A belt 39 connects the loose pulley 32 with a winding shaft 40 journaled on the lower part of the frame and carrying a V-pulley 41. A lever 42 is pivoted at its lower end 20 on the frame of the machine for movement transversely of the machine and projects above the machine in a position to be grasped by the hand. Near its pivotal point the lever 42 has a small idler guide pulley 43 mounted thereon, and adjacent to the rear rims of the bobbins 7 the lever 42 carries a small pulley 44 whose axis is parallel with the axes of the bobbins 7 and whose periphery is provided with a shallow belt-groove. 25 A round or cylindrical winding belt 45 runs over the V-pulley 41 on the winding shaft 40 and, being guided at an intermediate point at one side by the guide pulley 43, passes upward over the small pulley 44, and 30 projects from the shallow groove therein in proximity to the V-grooved rear rims of the bobbins 7, but out of contact therewith when the lever 42 is in its middle position, as shown in the drawings. When the usual 35 main driving belt 46 is shipped to the loose pulley 32, thereby stopping the chenille-forming operation of the machine, including the stoppage of the fliers 4-5 and the feed-regulating rollers 8; if the lever 42 be pulled 40 to one side, the winding belt 45 at the point where it passes over the small pulley 44 will be brought into contact with the peripherally grooved rim of the corresponding bobbin 7 to effect its rewinding with a supply of sur- 45 face thread *c*; and if the lever 42 be pulled to the other side, the other bobbin 7 will in like manner be rewound. The lever 42 may be locked in either of these bobbin-winding positions, or in the middle non-operative 50 position shown in the drawings, by means of a clamp 47 controlled by a clamp bolt having a wing nut 48 to grip a strap 49 forming also a gear cover. The thread-replenishing 55 rotation of the bobbins 7 will be in a clockwise direction as viewed from the front of the machine and as indicated by the arrow on the small pulley 44 (Fig. 3), the bobbins, of course, rotating oppositely to this pulley.

To equalize the braking effect on the bobbins 7 in the chenille-producing operation,

the brake cord 38 should be anchored at a point between the bobbins 7, and in the machine illustrated it is shown as anchored to a stud carried by the lever 42, this point of anchorage of the cord being merely incidental and a matter of convenience of construction. 70

Lubrication of each flier and its bobbin, while protecting the threads or yarns, is provided for by means of a thread-guiding tube 75 or bushing 50 (Fig. 7), having enlarged end portions which have a fluid-tight fit in the bore of the arbor 1, but in its middle portion and throughout most of its length being of smaller external diameter than the internal 80 diameter of the bore of the arbor, so as to thereby provide an annular oil space. On its upper side at a readily accessible point, shown as near its rear end, the arbor is provided with an oil inlet opening into the 85 annular oil space. Within the flier sleeve 4 the arbor 1 is shown as provided with oil outlets for lubricating such sleeve, the latter also being provided with oil passages or perforations adapted to register or communicate with the oil outlets in the arbor 1 for lubricating the bobbin 7 which covers the oil passages in the sleeve 4. Both the primary binder thread *a*, passing through the arbor 1, and the surface thread *c*, carried by 90 the bobbin 7, are by means of this construction completely protected from the oil used for lubricating the flier and bobbin. 95

The tension pulleys 10 that control the feed of the secondary binder thread *b* are 100 fixed on a transverse shaft 51 driven at the proper rate by means of a gear 52 and intermediary idler pinion 53 from the feed shaft 18 for the feed-regulating rollers 8. The transverse shaft 51 also carries a cone pul- 105 ley 54 for propelling the usual trolley employed to carry away the lengths of chenille as fast as formed. A large cone pulley 55, shown in the drawings as mounted on a counter-shaft 56 driven from the main shaft 110 30 by means of a sprocket chain 57, is for driving the usual twisting spindle of the trolley, which twists the chenille to bring out the surface loops formed from the surface thread *c* and to bind these loops be- 115 tween the binder threads *a* and *b*.

A few of the more prominent advantages of the hereinbefore described machine embodying my invention will be briefly noted.

For each chenille-forming mechanism different sizes and kinds of yarn or thread may be used and also different sizes of loop-forming pins may be employed to produce correspondingly different sizes and textures of chenille by the operation of each chenille-producing mechanism, irrespective of the operation of any other chenille-producing mechanism in the machine. The bobbins carrying the loop-forming surface thread or yarn may be quickly refilled without the 125 130

usual necessity of having to remove them from their operative thread-supplying position on the fliers, and the fliers and bobbins may be properly and safely lubricated 5 while in their operative positions with the threads or yarns in place for producing chenille.

It is obvious that various modifications may be made in the construction shown in 10 the drawings and above particularly described within the principle and scope of my invention.

I claim:

1. In a chenille machine, the combination 15 of a stationary loop-forming pin, a flier for winding a surface thread on the loop-forming pin, and a bodily yieldable driven feed-regulating roller for controlling the feeding of the coils of the surface thread from 20 the loop-forming pin.
2. In a chenille machine, the combination 25 of a plurality of stationary loop-forming pins, a flier for each loop-forming pin for winding a surface thread on the loop-forming pin, a separate feed-regulating roller co-operative with each loop-forming pin to control the movement of the coils of the surface thread therefrom, independent means for varying the co-operative relationship of each feed-regulating roller and its 30 loop-forming pin, and means for driving the feed-regulating rollers.
3. In a chenille machine, the combination 35 of a plurality of stationary loop-forming pins, a flier for each loop-forming pin for winding a surface thread on the loop-form-

ing pin, means for supplying a primary binder thread to each loop-forming pin within the coils of the surface thread, means for supplying a secondary binder thread to 40 each loop-forming pin at the outside of the coils of the surface thread, such latter means including for each loop-forming pin a rigid-surfaced yieldable feed-regulating roller co-operative with the loop-forming pin 45 for controlling the movement of the coils of the surface thread therefrom; means for each loop-forming pin for independently varying the co-operative relationship of the feed-regulating roller and its loop-forming 50 pin, and means for driving the feed-regulating rollers.

4. In a chenille machine, the combination 55 of a rotative flier, a thread-carrying bobbin rotatively mounted co-axially with the flier for supplying thread to the flier, and mechanism for winding thread on the bobbin while the bobbin is in the thread-supplying position relatively to the flier.

5. In a chenille machine, the combination 60 of a rotative flier, a thread-carrying bobbin rotatively mounted co-axially with the flier for supplying thread to the flier, and mechanism for selectively rotating at will either the flier to take thread from the bobbin or 65 the bobbin to take thread thereon.

In testimony whereof I have affixed my signature in presence of two witnesses.

CHARLES WIEBKE.

Witnesses:
